HEAT EXCHANGER

George T. Jacocks, New Rochelle, and Robert E. Giauque, New York, N. Y., assignors to Heat Transfer Products, Inc., New York, N. Y., a corporation of New York

Application December 6, 1941, Serial No. 421,914

4 Claims. (Cl. 220—55)

This invention relates to heat exchangers.

A principal object of this invention is the production of a device of the type specified which will be simple and inexpensive to construct, efficient in operation, and afford unusual facilities for disassembling.

Other objects and advantages will appear as the description of the particular physical embodiments selected to illustrate the invention progresses and the novel features will be particularly pointed out in the appended claims.

In describing the invention in detail and the particular physical embodiments selected to illustrate the invention, reference will be had to the accompanying drawings and the several views thereon, in which like characters of reference designate like parts throughout the several views, and in which:

Figure 1 is a side elevational view of a heat exchanger embodying the invention, some parts being broken away to more clearly show the construction; Fig. 2 is a fragmentary top plan view of the device as shown by Fig. 1; Fig. 3 is a view of the end of the device shown by Fig. 1 as viewed from the right hand end thereof; Fig. 4 is a fragmentary view of the device of Fig. 1 drawn to larger scale; Fig. 5 is a cross-sectional view on the plane indicated by the line V—V of Fig. 4, viewed in the direction of the arrows at the ends of the line; Fig. 6 is a longitudinal sectional view on the plane indicated by the line VI—VI of Fig. 4, viewed in the direction of the arrows at the ends of the line; Fig. 7 is a view corresponding to Fig. 4 exhibiting a modified form of the invention; Fig. 8 is a cross-sectional view on the plane indicated by the line VIII—VIII of Fig. 7, viewed in the direction of the arrows at the ends of the line.

The device, in general, is of the ordinary heat exchanger form in that it comprises a hollow cylindrical metal body designated generally by 1, provided with: a "bundle" 2 serving the function of the ordinary tube bundle; an inlet 3 to one header space giving access to the interior of the tubes of the bundle and an outlet 4 from another header space giving access to the interior of the tubes, said header spaces being separated by a partition 5; an inlet 6 and an outlet 7 for the fluid surrounding the outside of the tubes of the bundle 2. It is, of course, understood that the left hand end of the bundle 2, as viewed in Fig. 1 is arranged in a conventional manner or in accordance with the invention similarly to the right hand end, insofar as applicable.

In the construction shown in Figs. 1 to 6 in-

clusive, the shell is interrupted at 7 entirely around the circumference and a gasket ring 8 extending circumferentially around the shell is attached thereto, as by welding 9.

5 The cylindrical body 1 is continued beyond 7 by the shell extension 10 which is also welded to the gasket ring 8 as at 11.

The extension 10 is formed with two cut-away portions, 12 and 13, at opposite diametrical points. The spaces formed by these cut-away portions extend from the extreme right hand outer end of the extension 10, as viewed in Fig. 1, to the point 14 and are of a width sufficient to pass the nozzle outlet 3, at its diameter 15, longitudinally of the shell.

The nozzle outlet 3 and nozzle outlet 4 are welded to channel 16 as at 17 and 18. The channel is in the general form of an annulus substantially fitting the inner surface of the extension 10, and is attached preferably by welding at 19 and 20 to head 21.

20 After extension 10 is attached, as at 11 and cut outs 12 and 13 are removed, the channel 16 with attached nozzle outlet 3 and nozzle outlet 21 14 is slipped into place longitudinally of the cylinder 1 and then the portions 12 and 13 may be replaced, if desired.

The extension 10 has through orifices, as 22, formed at spaced intervals around it.

25 30 A retaining ring 23 is positioned in the end of extension 10 and is formed with orifices 24 corresponding to orifices 22.

At the time of making the complete assembly, the bundle 2 is first pushed into the cylinder 1, with the tube head 25 bearing against an annular gasket 26 placed against gasket ring 8. A gasket 27 is then placed on the other side of the head 25. Then nozzle channel 16 is put into place. After ring 23 is put in place, key locks 28 are fitted into the orifices 22 and 24 with the shoulders 29 and 30 resting against the inside surface of the retaining ring and the outside surface of the extension 10, respectively.

35 40 In order to bind all parts together fluid tight, the keys 28 are placed in position with the limiting shoulder 30 resting against retaining ring 23. The keys 28 have a threaded through orifice into each of which is threaded a threaded jack screw, as 31. The jack screw has an unthreaded portion 32 which passes freely through the through orifice 24 in the key lock 28.

45 50 When the parts are all in the position as shown by Figs. 1 and 4, the jack screws 31 are tightened and by bearing against the channel head 21 force that head inwardly and so force

the channel 16 inwardly against gasket 27 and the tube head inwardly against gasket 26 and gasket ring 8 making all parts fluid tight.

When removing the head, the jack screws 34 are backed out sufficiently to have their inner ends clear the key locks 28, whereupon the keys may be removed and then the key locks may be removed, thus allowing the retaining ring 23, the nozzle channel 16 and the tube head and bundle 2 to be removed.

The left hand end of the cylindrical member 1 may be arranged in the ordinary or usual manner and may have the usual head affixed therein in any or usual manner. It may also be attached, if desired, by a construction similar to the construction of head 21 insofar as the keys, key lock and jack screws are applicable.

In Figs. 6, 7 and 8, a modified construction is shown. In this construction the head 37 is separate from the channel 38 which carries the nozzle as 39.

In the modified construction, orifices, as 40, corresponding to orifice 22 of Fig. 1, are formed in the extension 41, but the key and key lock is made in a single piece. The key is designated 42 and has a tang extending through the orifices as 40, and corresponding ring orifices 43. Each of the keys has an extending arm provided with a groove 45. The grooves of the keys receive a jack screw retaining ring 46, pierced at intervals, as at 47, to receive a jack screw. The jack screws, as 48, are received in the through threaded bore 49 of the key and pass through an unthreaded bore 47 of the retaining ring 46.

In the modified form the channel 38 is separate from the channel head 37 and gaskets are placed at 50, 51 and 52.

Although we have particularly described one particular physical embodiment of our idea of means and a modified form thereof, nevertheless, we desire to have it understood that the forms selected are merely illustrative and do not exhaust the possible physical embodiments of the idea of means underlying our invention.

What we claim as new and desire to secure by Letters Patent of the United States, is:

1. A heat exchanger, including, in combination: a hollow cylinder, formed with a plurality of spaced orifices through its wall; a head for the cylinder; an abutment within the hollow cylinder for restraining the inward movement of the head and means for forcing the head inwardly including keys, each having one end projecting into an orifice and the other end positioned over the head, each key having a through threaded orifice; a threaded jack screw passing through each key and bearing on the head whereby the head is forced inwardly; and key locks, one associated with each key and between the key and the head and having one end projecting into an orifice and the other end over the head, each key lock formed with a lip lying

along the outside of the cylinder and with a through orifice receiving a jack screw and a retaining ring provided with through orifices corresponding to the orifices in the cylinder and positioned inside the cylinder and receiving each of the keys and key locks.

2. In a heat exchanger, in combination: a hollow body; an abutment within the body; a head for the end of the body; means for forcing the head toward the abutment including a plurality of jack screws; a plurality of keys each formed with a through threaded orifice for receiving a jack screw with one end of the jack screw bearing against the head; the hollow body formed with a plurality of through orifices in its wall, each of the keys having a portion projecting into an orifice and a portion containing the through bore overlying the head; a lock for locking the keys in position, said lock having a portion extending through an orifice in the wall and a lip overlying the wall and having a through orifice through which a jack screw extends.

3. In a heat exchanger, in combination: a hollow body; an abutment within the body; a head for the end of the body; means for forcing the head toward the abutment including a plurality of jack screws; a plurality of keys each formed with a through threaded orifice for receiving a jack screw with one end of the jack screw bearing against the head; the hollow body formed with a plurality of through orifices in its wall, each of the keys having a portion projecting into an orifice and a portion containing the through bore overlying the head; a lock for locking the keys in position, said lock having a portion extending through an orifice in the wall and a lip overlying the wall and having a through orifice through which a jack screw extends and retaining means to hold the keys and key locks in position.

4. In a heat exchanger, in combination: a hollow body; an abutment within the body; a head for the end of the body; means for forcing the head toward the abutment including a plurality of jack screws; a plurality of keys each formed with a through threaded orifice for receiving a jack screw with one end of the jack screw bearing against the head; the hollow body formed with a plurality of through orifices in its wall, each of the keys having a portion projecting into an orifice and a portion containing the through bore overlying the head; locks for locking the keys in position, said locks each having a portion extending through one of said orifices in the wall and a lip overlying the wall and having a through orifice through which a jack screw extends; and a retaining ring formed with through orifices in which the respective keys and key locks are positioned.
